GLAZIER'S TOOL

Anders Gunnar Anderson, Stoneham, Mass.

Application October 6, 1934, Serial No. 747,232

5 Claims. (Cl. 18—3.5)

This invention relates to glazier's tools, and more particularly to tools especially adapted for use in the setting of glass panes in door, window, or other frames, and the removing of panes therefrom.

In the setting of a pane of glass in a frame, it is customary first to place the pane in the rabbeted frame portion, then to place the well known triangular glazier's points in the frame, and then to apply a retaining bead or strip of putty in the angle between the edge of the pane and the adjacent frame portion. To remove a pane, as for example when broken, it is necessary to strip out the old and often tenaciously clinging strip of putty.

An object of my invention is to provide a tool including in cooperative relation a putty knife element, a hammer element for driving glazier's points, and a putty-removing element, thereby embodying in a single organized unit all the tool equipment needed for the setting or removing of glass panes.

Another object is to provide a tool of the character referred to in which the relative arrangement of parts is such as to permit the use of a small sized hammer element adapted to easily be moved into corners such as defined by the angle between a pane and the associated framing, the putty-removing element being disposed remotely from the hammer but in such manner that its weight augments that of the hammer so as to increase the striking effect of the latter.

Further objects are to provide a hammer element and a putty-removing element both of novel and improved form. Other objects will be apparent from the following description, the appended claims and the accompanying drawing, in which:

Figure 1 is a perspective view showing a tool embodying my invention in use for driving glazier's points;

Figure 2 is a perspective view showing my improved tool in use for removing putty;

Figure 3 is a plan view with part of the handle removed;

Figure 4 is a sectional view taken on the line 4—4 of Figure 3;

Figure 5 is a sectional view taken on the line 5—5 of Figure 3;

Figure 6 is a detail view of a hammer element;

Figure 7 is a detail view of a putty-removing element;

Figure 8 is a sectional view taken on the line 8—8 of Figure 6; and

Figure 9 is a sectional view taken on the line 9—9 of Figure 7.

The embodiment of the invention shown in the drawing for the purposes of illustration includes a handle A, a blade or putty knife element B, a

hammer element C, and a putty-removing element D.

The handle A, which may be of any suitable material such as wood, is divided or split into sections 1 and 2 between which is secured the blade B, the latter terminating somewhat above the lower end of the handle sections as viewed in Figures 3 and 4. The sections 1 and 2 are formed at their lower ends with engaging pads 3. Suitable securing means, such as rivets 4, hold the handle sections and the blade in assembled relation.

Secured to the blade and disposed between the handle sections are means for mounting the hammer element C and putty-removing element D pivotally with respect to the handle. The means for mounting the putty-removing element D includes a block 5 which abuts the lower face (as viewed in Figure 5) of the blade B and a plate 6 which in turn abuts the lower face of the block 5. The block 5, plate 6 and blade B are secured in the relation shown by means of the rivets 1, while a pintle 8 extending between the blade and the plate 6 mounts the putty-removing tool D for swinging movement relative to the handle. A leaf spring 9 set in the block 5 engages a heel 10 on the putty-removing tool D and serves releasably to hold it either in open or closed position, that is, in an open position in which the element D is extended alongside of the blade B or in a closed position in which the element D is nested between the handle sections.

The means for mounting the hammer element C includes a block 11 which abuts the upper face (as viewed in Figure 5) of the blade B, and a plate 12 which abuts the upper face of the block 11. The block, plate and blade are secured together with rivets 13, and a pintle 14 extending between the plate 12 and the blade mounts the hammer element for swinging movement relative to the handle. A leaf spring 15 engages a heel 16 on the hammer element C and serves releasably to hold the latter either in open or closed position, that is, in an open position in which the hammer element lies alongside the blade B, or in a closed position in which the hammer element is nested between the handle sections.

The hammer element C comprises a shank 17 provided at its outer end with a head 18 having a substantially flat driving surface 19 in a plane substantially perpendicular to the plane of the blade B when the hammer element is in open position. The face of the head 18 adapted to be disposed nearest a glass pane when the tool is in use is tapered off at 20 towards its outer end corner with respect to the plane of blade B and the plane containing the driving surface 19 is disposed at an obtuse angle to the plane containing the surface 20 for a purpose to be described later. The head 18 is formed with a slot 21

adapted to receive the edge portion of the blade B for protecting the blade against injury during use of the tool as a hammer and also for holding the hammer element in relatively fixed position 5 with respect to the handle. The arrangement is such that the blade forms a support for the hammer element and effects a substantially rigid connection between the latter and the handle.

The putty-removing element D includes a 10 shank 22 provided at its outer end with a head 23 formed with a slot 23a adapted to receive the adjacent edge portion of the blade for protecting the latter against damage during use of the tool for removing putty and also for effecting

15 a substantially rigid connection between the putty-removing element and the handle when the former is in use. The head 23 is formed with a cutting portion 24 which extends generally inwards towards the inner end of the shank and 20 which is defined by cutting edges 25 and 26, the cutting edge 25 extending along a face of the head lying in a plane substantially parallel to the plane of the blade B, and the cutting edge 26 extending in a plane containing the outer-most side 25 face of the head. In other words, the edges 25 and 26 bound surfaces lying in planes which are substantially perpendicular to each other. These cutting edges converge at a nose 27, and the surface 30 between the cutting edges is inclined with respect to both of the planes referred to, so that putty being removed by the cutting edges will be deflected away from the tool, the latter having the action of a planer.

When it is desired to use the tool as a putty 35 knife only, the elements C and D are swung into their closed position in which they will be housed between the handle sections leaving only the blade exposed. The blade may then be used in the customary manner.

40 When it is desired to employ the tool for driving glazier's points, the hammer element C is moved to its open position as shown in Figure 1, and the putty-removing element D may also be moved to its open position in order to augment 45 the weight of the hammer element so as to increase its driving effect. It will be observed that because of the tapered-off face or slide-surface 20 of the hammer element, the latter may readily be moved into the angle between the frame 50 29 and the glass pane 30 so as to strike the glazier's points 31 without striking the frame. The handle is held at such an angle as to extend outwardly somewhat from the pane 30, the particular angle being that which will cause the tapered off face 20 to be substantially parallel to the plane of the pane. The putty-removing element D being located directly opposite the hammer element C will augment the driving action 55 of the latter even though it is disposed somewhat remotely therefrom and will not interfere with moving the hammer into the angle between the frame and the pane.

60 When it is desired to remove old putty, the hammer element may be moved to its closed position and the putty-removing element placed in the angle between the pane and the frame in the manner shown in Figure 2, from which it will be clear that movement of the tool downwardly with respect to the frame will strip the putty bead 32 65 away from the pane and from the frame.

70 It is believed to be apparent from the foregoing description that I have provided in a single unit a glazier's tool including parts arranged in co-operative relation and adapted to perform all of 75 the operations incident to the setting or removal

of panes of glass in frames of various kinds. The putty-removing element and the hammer element when in open position protect the corners of the putty blade B to prevent bending of the latter when the tool is employed for hammering purposes, and the arrangement of the parts is such that the putty-removing element assists in the driving action of the hammer element without interfering with the latter's being moved up into the angle between the frame and the pane.

Various modifications can be made in the specific construction and relative arrangement of the parts without departing from the invention as defined in the claims.

I claim:

1. In a glazier's tool, the combination of a handle; a putty knife element connected thereto; a hammer element pivotally connected to the handle and when in operative position abutting against one side edge of said knife element; and a putty-removing element pivotally connected to said handle and adapted to abut against the side of said knife element opposite the hammer element.

2. In a glazier's tool, the combination of a handle; a putty knife element connected thereto; a hammer element pivotally connected to the handle and when in operative position abutting against one side edge of said knife element; and a putty-removing element pivotally connected to said handle and adapted to abut against the side of said knife element opposite the hammer element, said hammer element and said putty-removing element each comprising a shank having its inner end pivoted to the handle, and a head at the other end of the shank formed with a slot 35 adapted to embrace the associated side edge portion of the knife element.

3. In a glazier's tool, the combination of a handle; a putty knife element connected thereto; a hammer element pivotally connected to the handle and when in operative position abutting against one side edge of said knife element; and a putty-removing element pivotally connected to said handle and adapted to abut against the side of said knife element opposite the hammer element, said hammer element comprising a head, one of the faces thereof being tapered off towards its outer end corner with respect to the plane of said knife element.

4. In a glazier's tool, the combination of a handle; a putty knife element connected thereto; and a putty-removing element comprising a shank having its inner end pivotally connected to the handle and at its outer end having a head provided with a slot adapted to embrace one side edge portion of the knife element, said head being formed with a cutting portion extending generally inwards towards said handle and being defined by two converging cutting edges which lie respectively in planes substantially at right angles to each other.

5. A glazier's tool for removing putty from windows or the like comprising a shank; and a head at one end of the shank formed with a cutting portion extending laterally beyond one side of the shank and generally inwards towards the other end of the shank and having two cutting edges which lie respectively in planes substantially perpendicular to each other, said two cutting edges converging to form a nose which extends generally inwardly towards the opposite end of the shank, and the surface between said edges being inclined with respect to both of said planes.

ANDERS GUNNAR ANDERSON.
